UNITED STATES PATENT OFFICE.

WILLIAM K. MILLER, OF CANTON, OHIO.

IMPROVEMENT IN HARVESTERS.

Specification forming part of Letters Patent No. 139,597, dated June 3, 1873; application filed March 14, 1873.

To all whom it may concern:

Be it known that I, WILLIAM K. MILLER, of Canton, in the county of Stark and State of Ohio, have invented certain new and useful Improvements in Harvesters, of which the following is a specification:

My present invention relates to harvesters of the class known as hinge-joint machines. Its object is to improve the efficiency of the machine; and the subject-matter claimed is hereinafter specifically set forth.

In the accompanying drawings, which show all the improvements hereinafter claimed as embodied in one machine, Figure 1 is a plan, with the driver's seat and portions of the platform removed; Fig. 2, a side elevation, with the cutting apparatus and inner drive-wheel removed; Fig. 3, a longitudinal vertical central section through the machine; Fig. 4, a rear elevation of part thereof. Figs. 5, 6, and 7 show details of the device for raising and lowering the front end of the coupling-frame; and Fig. 8, a transverse section through the coupling-frame on the line $x x$ of Fig. 1; Fig. 9, a longitudinal vertical section through the shoe; Fig. 10, a section through the counter-shaft, showing the gearing and shipper.

Two main wheels, A A', turn loosely on an axle, B, with which they are connected by suitable locking-ratchets. The axle turns in bearings in a main frame, C, by preference of cast metal, and of the form shown in the drawings. A tie-rod, c, connects the main axle with a projecting arm, c¹, on the inner front corner of the main frame, to brace the parts. A similar tie-rod, c², connects the front and rear parts of the frame below the axle. A tongue, D, is pivoted to the frame at d, resting in a socket in the frame, which braces it against lateral strains. A set-screw, d¹, passing up through a bracket, d², beneath the tongue, serves to raise or lower the tongue relatively to the front end of the frame.

This device rocks the main frame on the axle. The front end of a drag-bar, E, moves up and down in a guide, e, located on the front of the frame and centrally between the driving-wheels, being controlled by a link, e¹, crank-arm E¹, hand-lever E², and a spring-detent of well-known construction.

Figs. 1 and 2 show the details of this rock-

ing device. The lever, it will be noted, is mounted on one side of the main frame, where it is more conveniently reached by the driver than if mounted directly over the drag-bar. The drag-bar is, by preference, made of comparatively thin wrought metal, with a longitudinal corrugation, e³, to stiffen it. (See Fig. 8.) A coupling-arm, F, is connected to the frame at one end by a swivel-joint, f, and at the other is riveted to the drag-bar. A stiffening-plate, f', Fig. 8, is secured to the under side of the drag-bar and coupling-arm. A strong but light coupling-frame is thus secured. The joints of the coupling-arm and drag-bar, it will be observed, lie in the central line or longitudinal axis of the machine, which, in this instance, is coincident, or nearly so, with the crank-shaft. The lower end of the coupling-frame is bifurcated, forming lugs, to which a shoe, G, is pivoted, as shown. A finger-beam, H, and platform I are secured to this shoe in the usual way. A grain-wheel, J, supports the divider end of the platform. The cutting apparatus is of the usual Hussey type.

In mowing, the grain-wheel and platform are removed, and the cutting apparatus conforms freely to the undulations of the ground. In harvesting, it is desirable that the inner shoe should be carried above the ground, that its joint should be free to flex to enable the heel end of the cutting apparatus to rise over elevations, and yet that the divider end of the finger-beam should not rise above a given point.

These capabilities are especially advantageous in using an automatic rake—such, for instance, as the one shown in another division of this application, filed simultaneously herewith—as the limitation of the rising of the divider end of the cutting apparatus prevents the rake from striking the machine and becoming injured. To this end I use a stop, consisting of a bar, K, pivoted to a lug on the shoe, and adjustable by means of a creased clutch, k. This bar rests on the coupling-frame, and thus limits the downward flexure of the joint at the heel end of the cutting apparatus, while allowing it freely to rise, at the same time limiting the rise of the outer end of the finger-beam.

The inclination of the guard-fingers, it will

be observed, can be varied by moving the front end of the drag-bar E up or down by means of the hand-lever E², as before explained, and this range of motion is increased by the tongue adjustment hereinbefore described.

A lifting hand-lever, L, pivoted on the tongue carries a sector, l, connected by a rod and chain, l¹, with a similar sector, L¹, on a rock-shaft, l², mounted on an arm, C', projecting from the main frame. A second sector, L², on this rock-shaft is connected by a chain, l³, with the coupling-frame. The finger-beam is thus raised, lowered, or suspended.

A spur-wheel, M, on the main axle drives a corresponding pinion, m, on a counter-shaft, n, carrying a bevel-wheel, N, which drives a bevel-gear, o, on a crank-shaft, O, which drives a pitman, P. The mechanism is thrown into or out of gear by a shifting-clutch on the counter-shaft, actuated by a shifter, R. (See Fig. 10.) The pitman is connected with the sickle eye by means of a tubular socket, p, in which it turns. An arm, p', depending from this socket is perforated at right angles there-

to, and a bolt passes through this arm and the sickle-eye, thus forming a swivel-joint, which permits the cutting apparatus to rock freely without twisting the pitman. The joint between the arm and sickle-eye can easily be tightened up to compensate wear and prevent rattling. The cover S is elevated somewhat above the main frame, to which it is connected by hinges s, by which means it can readily be lifted up to afford access to the gearing.

The operation and advantages of my improvement will be apparent from the foregoing description.

I claim as my invention—

The adjustable locking stop-bar K, mounted on the shoe and resting on the coupling-frame, as set forth.

In testimony whereof I have hereunto subscribed my name.

WM. K. MILLER.
